CLAIM

The ornamental design for a wood pellet dispenser, as shown and described.

DESCRIPTION

FIG. 1 is a top front perspective view of a wood pellet dispenser;

FIG. 2 is a front elevation view thereof;

FIG. 3 is a rear elevation view thereof;

FIG. 4 is a right elevation view thereof, with the left elevation view being a mirror image thereof;

FIG. 5 is a top elevation view thereof; and,

FIG. 6 is a bottom elevation view thereof.

The broken lines shown in the drawings depict an exemplary window and a power cord that form no part of the claimed invention.
